WELL PACKER

Reuben C. Baker, Coalinga, Calif., assignor to
Baker Oil Tools, Inc., Vernon, Calif., a corpora-
tion of California

Application April 29, 1946, Serial No. 665,811

16 Claims. (Cl. 166—11)

This invention relates to well tools, and more particularly to well packers employed in the cementing, acidizing, testing, washing, production, etc., of oil and gas wells.

It is an object of the present invention to provide a well packer more economical to manufacture and capable of assembly and disassembly with greater facility.

A further object of the invention is to provide a well packer whose packing element may be easily clamped to and released from the packing member on which it is mounted.

Still another object of the invention is to provide a well packer having a supporting member on which a plurality of packing elements may be mounted in such fashion as to be individually clamped thereto and yet easily and rapidly released when disassembly is desired.

This invention has other objects that will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Figure 1 is a longitudinal section through a well tool embodying the invention;

Figure 2 is a longitudinal section on an enlarged scale of part of the well tool;

Figure 3 is a cross-section taken along the line 3—3 in Figure 2;

Figure 4 is an exploded view of a lock nut device forming part of the tool; and

Figure 5 is a fragmentary longitudinal section, on an enlarged scale, of part of the tool.

As disclosed in the drawings, the well tool consists of a body suitably secured, as by threading, to the lower end of a string of tubing or drill pipe A, by means of which the tool is conveyed through a well casing B to the desired operating point. The body consists of an upper body member 10, a lower body member 10a, and an intermediate body member 11 connecting the upper and lower members together in spaced relation. The general type of well packer shown is described and claimed in the patent application of Charles E. Costello, Serial 391,548, filed May 2, 1941, for "Well Devices," now Patent No. 2,466,305.

The upper and lower portions of the tool are substantial duplicates, being connected to the intermediate body member 11 in opposed rela-

tion. A description of the upper portion should suffice for the lower portion as well.

The upper body member 10 includes an elongate mandrel or nipple 12 having a sub 13 secured on its upper end and a lower ported sub 14 secured to its lower end. One or more packing cups 15, 16, 17 of rubber or similar material are secured on the mandrel with the lower cups 15, 16 facing downwardly. These packing cups are adapted for slidable sealing engagement with the wall of the well casing B to prevent upward flow of fluid between the upper body member 10 and the casing.

An upper by-pass tube 18 is positioned within the upper body member 10 to provide an annular space 19 therewith. Its upper end is threaded into a by-pass T 20, which is suitably secured, as by welding, to the upper by-pass sub 13, through which it opens outwardly into the tubing-casing annulus 21 above the upper packings. The lower end of the by-pass tube extends through an inner flange 22 on the lower sub 14, containing a rod packing 23 pressed in leakproof engagement against the exterior of the tube 18 by a suitable packing nut 24 to prevent downward flow of fluid through the annulus 19 beyond the flange 22.

As stated above, the construction of the lower tool portion is substantially the same as the upper, with the parts facing in the opposite direction, preventing fluid passage between the lower body member 10a and casing wall in a downward direction. Upward flow of fluid through the lower annulus 19a beyond the flange 22a is prevented by the flange 22a, packing 23a and packing nut 24a surrounding the lower by-pass tube 18a. For convenience of designation, the lower parts are numbered the same as the corresponding upper parts, with the suffix "a" added.

The upper and lower tool portions are held together in spaced relation by the intermediate body member 11, which actually forms part of the by-pass of the tool. This intermediate body member is secured to the upper and lower subs 14, 14a, and may be made of any length desired, depending upon the spacing required between the upper and lower packing cups 15, 15a. The by-pass around the packings extends from a point outside the tool below the lower packing 17a to a point outside the tool above the upper packing 17. More specifically, this by-pass passage is constituted by the lower T 20a, lower by-pass tube 18a, intermediate body member 11, upper by-pass tube 18, and upper by-pass T 20.

The upper sub 14 is provided with one or more upper outlets or ports 25 adjacent the packing cup 15, and the lower sub 14a is similarly provided with one or more lower outlets or ports 25a adjacent the lower packing cup 15a. Fluid cannot pass directly from the upper body annulus 19 to the lower body annulus 19a, because of the flanges 22, 22a and packings 23, 23a around the by-pass tubes 18, 18a, but must pursue an indirect course. The fluid is pumped downwardly through the tubing A, into the upper body member annulus 19, exiting through the upper ports 25 into the localized annular zone 26 defined by the upper and lower packings 15, 15a, and by the intermediate body member 11 and casing B. This fluid may flow downwardly through this zone and enter the lower body member 10a through the lower ports 25a, where the fluid can pass downwardly through the annulus 19a around the lower by-pass tube 18a and into a valve body or housing 27 screwed into the lower end of the lower sub 14a. The fluid may then pass through the valve outlets or ports 28 in the housing to the exterior of the tool below the lower packing cup 17a, from where it may flow upwardly into the lower by-pass T 20a, through the lower by-pass tube 18a, intermediate by-pass body member 11, upper by-pass tube 19, and upper by-pass T 20, into the tubing-casing annulus 21 above the upper packing cup 17.

The allowing of the fluid to pursue the course just described is dependent upon control of the flow of fluid through the valve ports 28 at the lower end of the tool. Such control is obtained through a valve mechanism including a valve stem 29 projecting upwardly into the housing 27 and adapted to engage a ball valve 30 capable of moving downwardly to engage a seat 31 suitably secured to the housing and positioned above the housing ports 28. The stem 29 exteriorly of and below the housing carries a suitable drag or friction device 32 adapted to engage the walls of the casing B and resist movement of the valve stem therewithin. When the valve stem 29 is in the lower position, shown in Figure 1, it is free from engagement with the ball valve 30, which may rest upon its seat 31 and prevent downward passage of fluid through the lower body 10a. Relative elevation of the valve stem with respect to the housing, as by lowering the connected body members 10, 11, 10a and housing 27 several inches, causes the upper end of the valve stem 29 to engage the ball 30 and lift it from the seat 31, permitting downward passage of fluid from the lower body 10a, through the valve seat 31 and valve ports 28 to the exterior of the tool.

The positions of the ball valve 30 with respect to its seat are determined by a lock device, which in the present instance includes a lock pin 33 secured to the valve stem and engaging in a lock slot 34 of inverted J or L form. When the valve stem is moved relatively upward within the valve housing the lock pin 33 may be positioned in the upper horizontal portion of the slot 34 to hold the ball valve 30 off its seat. Relative lowering of the valve stem 29, as permitted by placement of the lock pin 33 in the longitudinal slot portion, removes the stem from the ball valve 30 and allows the latter to engage its seat 31.

The tool described has a variety of uses. It may be disposed on opposite sides of casing perforations C, and cement slurry pumped down through the tubular string A into the upper body member 10 and out through the upper ports 25 into the localized zone 26 between the opposed

packing cups 15, 15a from where the cement slurry passes through the casing perforations C to cement the casing B in place. Displacement of cement through the perforations will occur upon elevation of the tubing string A and tool body 10, 11, 10a, 27 several inches to remove the valve stem 29 from engagement with the ball 30 and allow the latter to contact its seat 31, thus closing the annular passage 19a through the lower body member 10a.

After the required amount of cement slurry has been forced through the casing perforations, any excess can be removed from the tubing, tool and well casing by lowering the tool several inches to cause the valve stem 29 to elevate the ball 30 from its seat 31, which permits the excess slurry to flow downwardly from the tubing A through the upper body annulus 19 and port 25 into the localized zone 26 between the packing cups 15, 15a, thence flowing through the lower port 25a into the lower body annulus 19a, and around the check valve 30 and through the valve ports 28 to the exterior of the tool below the lower packing member 17a, from where the circulating fluid and cement slurry passes into the lower by-pass T 20a and up through the lower by-pass tube 18a, spacer pipe 11, upper by-pass tube 18 and upper by-pass T 20 into the tubing casing annulus 21 above the upper packer 17. If desired, the excess cement slurry may be circulated from the well bore by reversing the direction of flow described, that is, by initially pumping down through the tubing-casing annulus 21, through the tool and up through the tubing to the top of the well bore.

The well packer is constructed in such manner as to be economical to produce, assemble, dismantle and maintain. Each body member may include a single nipple 12 on which each cluster of packing cups is clamped.

Each nipple 12 is provided with threaded ends 35, 36 for coupling to the upper by-pass sub 13 and lower sub 14, and also with intermediate threaded portions 37, 38 to receive clamping devices 39, 40 holding the packing members 15, 16 securely on the nipple or body member. The threaded sections on the nipple are all cut into its exterior surface, so that the major diameter P of the threads is no greater than the diameter R of the external cylindrical surface 41 of the nipple. In other words, the threads 37, 38 are cut into the cylindrical exterior of the nipple. If three packing cups are used on each nipple, as shown in the drawings, the lower packing cup 15 is clamped between an abutting spacer sleeve 42 engaging the lower sub 14 and a cup-shaped thimble 43. A split or segmental clamp nut 44, 44 is placed on the threaded section 37 of the nipple and is prevented from lateral movement by a collar 45 having an internal tapered surface 46 cooperating with corresponding external tapered surfaces 47 on the segmental nut. The collar also has downwardly extending keys or ribs 48 projecting inwardly between the opposed ends 49, 49 of the nut segments 44, 44.

The intermediate packing cup 16 is clamped between a second spacer sleeve 50, whose lower end engages the lower collar 45, and a second cup-shaped thimble 51, which is engaged by a second segmental clamp nut 52 and collar 53 constructed in the same manner as the segmental nut 44, 44 and collar 45 described above. This segmental nut 52 is threaded on the second intermediate threaded portion 38 of the nipple. The third packer cup 17 is clamped between a lower cup-shaped thimble 54, engaging the second col-

lar 53, and a spacer sleeve 55, whose upper end engages a solid lock nut 56 threaded on the upper threaded portion 35 of the nipple.

The packing assembly just described may be rapidly and easily mounted on the nipple 12 in several ways, one of which will now be described. The nipple is first threaded tightly into the lower sub 14 and the first spacer sleeve 42 then slid over the upper end 35 of the nipple and into engagement with the lower sub 14. The lower packing cup 15 and thimble 43 may then be similarly moved over the nipple to its lower region, immediately below the threaded portion 37. The two halves 44, 44 of the segmental nut are then placed directly over the lower intermediate threaded portion 37 of the nipple with their threads properly engaging the nipple threads, and the lower collar 45 then placed over the upper end 35 of the nipple and over the segmental nuts 44, 44 with the keys 48, 48 positioned between their opposed ends 49, 49. The second set of elements, including the spacer sleeve 50, intermediate packing cup 16, thimble 51, segmental nut 52 and collar 53 are then similarly placed on the nipple, followed by the upper thimble 54, upper cup 17 and spacer sleeve 55. The solid lock nut 56 is then threaded on the upper nipple portion 35.

With all of the parts thus mounted in their approximate final positions on the nipple, the lower collar 45 is turned to screw the segmental nut 44, 44 on the threaded nipple portion 37 toward the lower sub 14, and thus clamp the lower packing 15 firmly between the spacer sleeve 42 and thimble 43. The screw threading described is transmitted from a suitable wrench (not shown) placed on the exterior of the collar 45, through the keys 48, 48 to the segments 44, 44, turning the segments and causing them to advance towards the lower sub 14 on the nipple threads.

When the lower packing 15 has thus been firmly clamped on the nipple, the intermediate packing 16 is similarly clamped in place by applying a wrench to the upper collar 53 and turning it in the proper direction to thread its cooperative segmental nut 52 along the upper intermediate threaded nipple portion 38 and toward the lower segmental nut 44, 44, until the intermediate cup 16 is firmly clamped in place. Thereafter, the wrench is applied to the solid nut 56 and the upper packing cup 17 clamped in place by advancing the nut 56 toward the upper segmental nut 52 and collar 53.

The by-pass tube 18 may now be threaded in the by-pass T 20, which has already been welded to the by-pass sub 13. This sub assembly may now be placed into and over the nipple 12, with the tube 18 passing into and through the center hole in the lower sub flange 22 and the by-pass sub 13 threaded on the upper end 35 of the nipple. The packing 23 is then placed around the by-pass tube 18 and firmly clamped in place by the packing nut 24.

The lower portion of the tool is assembled in a similar manner and the two major halves of the tool then secured to one another by the spacer pipe 11, forming a part of the by-pass. The valve assembly 27—33 may then be threaded into the lower end of the lower by-pass sub 13a.

In order to mate properly with the threads 37, 38 cut into the exterior of the nipple, the two halves 44, 44 of each segmental nut must function cooperatively with one another as a single nut. To produce this result, the threads on one segment are a continuation of the threads on

the other segment. One manner of achieving thread continuity is to first form the segmental nut as a single member and cut the threads in its interior. Thereafter, the single member is severed in two parts, as with a milling cutter, which insures practical continuity of the threads from one segment flowing properly into the thread in the other segment.

It is to be noted that the cooperative tapered surfaces 47, 46 on the two part segmental clamp nut 44, 44 and companion lock collar 45 diverge in the direction in which the nut is threaded on the nipple to effect clamping of the packing 15 between the thimble 43 and spacer sleeve 42. As above stated, a suitable wrench placed on the exterior of the collar 45 will cause its turning effort to be transmitted to the split or segmental nut 44, 44 through the keys 48, 48, and feed the nut along the nipple threads 37 to effect clamping of the packing cup on the nipple or body member 12. Engagement of the adjacent spacer sleeve 50 with the collar 45 will prevent its looseness and will cause it to exert a wedging action on the split nuts 44, 44, holding them inwardly in firm cooperative engagement with the nipple threads 37. Similarly, engagement of the uppermost thimble 54 with the upper collar 53 holds it in firm wedging engagement with the upper segmental nut 52 to insure against looseness of the assembly.

As shown in the drawings, there is very little difference in the length between each segmental nut and its companion collar. Actually the collar need only extend longitudinally a slight distance beyond the smaller end of the nut (a sixtieth of an inch will do), for engagement by the spacer sleeve or thimble and to be urged snugly into wedged contact with the segmental nut.

By virtue of the tool described, the lower body 40 assembly is the same as the upper body assembly, which makes the two assemblies interchangeable. Each packing is individually clamped on the mandrel, offering greater assurance against their becoming loose, or leakage occurring between the 45 packing cup and the nipple during operation of the tool. Moreover, the parts may be very quickly assembled in place, since it is not necessary to thread the entire exterior of the nipple, as in prior art devices, and then screw solid clamp nuts 50 along the whole length of the nipple into its proper clamping position against the packing cup thimble, which is a time consuming and tedious operation, especially when the length of the nipple is considered. Not only are savings in time thus effected, but additional savings in 55 manufacturing costs achieved through obviating the need for threading the entire exterior of the nipple. All that need be done is to select a nipple with a continuous cylindrical exterior of proper diameter and then thread this exterior at one or more spaced points, as desired.

Disassembly of the tool is easily effected by reversing the assembly procedure outlined above. Of course, the packing cups 15, 16, 17 may also be 65 disassembled by first removing the lower sub 14 from the nipple 12, which would then permit the spacer sleeve 42, cups, thimbles and collars to be moved downwardly off the nipple. In disassembly, after the lower sub 14 has been removed or loosened, the upper solid lock nut 56 may be backed away from the upper sleeve 55, which will then permit the upper collar 53 to be similarly backed away out of clamping relation with its companion segmental lock nut 52 and these latter 70 parts removed laterally from the mandrel 12.

The intermediate thimble 51, packing cup 16 and sleeve 58 may then be backed away from the lower collar 45 and segmental nut 44, 44, permitting the collar 45 to be moved back from the lower segmental nut 44, 44 and the two halves of the latter also removed laterally from the mandrel. The collars 45, 53, thimbles 43, 51, 54, spacer sleeves 42, 50, 55, and packing cups 15, 16, 17 are now loose on the nipple and may be removed therefrom in a downward direction.

Having thus described my invention, what I claim and desire to secure by Letters Patent is:

1. A packing assembly, including a body member having a threaded portion, a packing structure on said body member, abutment means engaging said packing structure on one side thereof, a segmental nut on said threaded portion engaging said packing structure on the other side thereof, and means engageable with the exterior of said nut to prevent its removal from said threaded portion.

2. A packing assembly, including a body member having a threaded portion, a packing structure on said body member, abutment means engaging said packing structure on one side thereof, a split nut on said threaded portion engaging said packing structure on the other side thereof, and means encompassing said nut to prevent its removal from said threaded portion.

3. A packing assembly, including a body member having a threaded portion, a packing structure on said body member, abutment means engaging said packing structure on one side thereof, a segmental nut on said threaded portion engaging said packing structure on the other side thereof, means encompassing said nut to prevent its removal from said threaded portion, said last-mentioned means having an inwardly directed projection disposed between adjacent ends of the segments of said nut.

4. A packing assembly, including a body member having a threaded portion, a packing structure on said body member, abutment means engaging said packing structure on one side thereof, a split nut on said threaded portion engaging said packing structure on the other side thereof, means encompassing said nut to prevent its removal from said threaded portion, said last-mentioned means having an inwardly directed projection disposed between adjacent ends of said split nut.

5. A packing assembly, including a cylindrical body member having an exteriorly threaded portion whose major diameter is no greater than the diameter of an adjacent unthreaded portion of said cylindrical body member, a packing structure on said body member, abutment means engaging said packing structure on one side thereof, a segmental nut on said threaded portion engaging said packing structure on the other side thereof, and means engaging the exterior of said nut to prevent its lateral removal from said threaded portion.

6. A packing assembly, including a cylindrical body member having an exteriorly threaded portion whose major diameter is no greater than the diameter of an adjacent unthreaded portion of said cylindrical body member, a packing structure on said body member, abutment means engaging said packing structure on one side thereof, a segmental nut on said threaded portion engaging said packing structure on the other side thereof, means encompassing said nut to prevent its removal from said threaded portion, said last-

mentioned means having an inwardly directed projection disposed between adjacent ends of the segments of said nut.

7. A packing assembly, including a body member having a threaded portion, a packing structure on said body member, abutment means engaging said packing structure on one side thereof, a segmental nut on said threaded portion engaging said packing structure on the other side thereof, said nut having a frusto-conical external surface, and means having a companion frusto-conical inner surface in engagement with the exterior of said nut to prevent its removal from said threaded portion.

8. A packing assembly, including a body member having a threaded portion, a packing structure on said body member, abutment means engaging said packing structure on one side thereof, a segmental nut on said threaded portion engaging said packing structure on the other side thereof, said nut having a frusto-conical external surface, means having a companion frusto-conical inner surface in engagement with the exterior of said nut to prevent its removal from said threaded portion, said last-mentioned means having inwardly directed projections disposed between adjacent ends of the segments of said nut.

9. A packing assembly, including a cylindrical body member having an exteriorly threaded portion whose major diameter is no greater than the diameter of unthreaded portions of said cylindrical body member on both sides thereof, a packing structure on said body member, abutment means engaging said packing structure on one side thereof, a segmental nut on said threaded portion engaging said packing structure on the other side thereof, said nut having a frusto-conical external surface, means having a companion frusto-conical inner surface in engagement with the exterior of said nut to prevent its removal from said threaded portion, said last-mentioned means having inwardly directed projections disposed between adjacent ends of said nut.

10. A packing assembly, including a cylindrical body member having an exteriorly threaded portion whose major diameter is no greater than the diameter of unthreaded portions of said cylindrical body member on both sides thereof, a packing structure on said body member, abutment means engaging said packing structure on one side thereof, a segmental nut on said threaded portion engaging said packing structure on the other side thereof, said nut having a frusto-conical external surface, a collar having a companion frusto-conical inner surface in engagement with the exterior of said nut to prevent its removal from said threaded portion, said collar having inwardly directed projections disposed between adjacent ends of said nut, one of said means engaging said collar to hold said frusto-conical surfaces in engagement with one another.

11. A well packer assembly, including a cylindrical body member having longitudinally spaced exteriorly threaded portions whose major diameters are no greater than the diameters of unthreaded portions of said cylindrical body member on both sides thereof, a first packing structure on said body member, a first abutment means engaging said packing structure on one side thereof, a first segmental nut on one of said threaded portions engaging said packing structure on the other side thereof, means encompassing said nut to prevent its removal from said threaded por-

tion, a second packing structure on said body member, a second abutment means engaging said encompassing means and also engaging said second packing means on one side thereof, a second segmental nut on said other threaded portion engaging said second packing structure on the other side thereof, means encompassing said second nut to prevent its removal from said second threaded portion, and means engageable with said last-mentioned means to hold said second segmental nut firmly on said second threaded portion.

12. A well packer assembly, including a cylindrical body member having an exteriorly threaded portion whose major diameter is no greater than the diameter of unthreaded portions of said cylindrical body member on both sides thereof, a packing structure on said body member, abutment means engaging said packing structure on one side thereof, a segmental nut on said threaded portion engaging said packing structure on the other side thereof, means encompassing said nut to prevent its removal from said threaded portion, a second packing structure on said body member engaging said encompassing means, and means engaging said second packing structure to clamp the same against said encompassing means.

13. A packing assembly, including a body, a packing structure on said body, a member engaging said packing structure on one side thereof, said body having a threaded portion on the other side of said packing structure and an adjacent unthreaded portion, the major diameter of said threaded portion being no greater than the diameter of said unthreaded portion, an abutment structure on said unthreaded portion, a segmental nut on said threaded portion engageable with one of said structures, and means engageable with the other of said structures and disposed over the exterior of said nut to prevent its removal from said threaded portion.

14. A packing assembly, including a body, a packing structure on said body, a member engaging said packing structure on one side thereof, said body having a threaded portion on the other side of said packing structure and an adjacent unthreaded portion, the major diameter

of said threaded portion being no greater than the diameter of said unthreaded portion, an abutment structure on said unthreaded portion, a nut comprising a plurality of separate segments on said threaded portion engageable with one of said structures, said nut having a frusto-conical external surface, and means engageable with the other of said structures and having a companion frusto-conical inner surface in engagement with the exterior of said nut segments to prevent lateral removal of said segments from said threaded portion.

15. A packing assembly, including a body member having a threaded portion, a packing structure on said body member, abutment means engaging said packing structure on one side thereof, a split nut on said threaded portion engaging said packing structure on the other side thereof, means encompassing said nut to prevent its removal from said threaded portion, and means on said body member for preventing removal of said encompassing means from said nut.

16. A packing assembly, including a body member having a threaded portion, a packing structure on said body member, abutment means engaging said packing structure on one side thereof, a nut comprising a plurality of separate segments on said threaded portion engaging said packing structure on the other side thereof, said nut having a frusto-conical external surface, securing means having a companion frusto-conical inner surface in engagement with the exterior of said nut segments to prevent lateral removal of said nut segments from said threaded portion, and means on said body member for holding said securing means in engagement with said nut segments.
